Samuel W. Barr.

UNITED STATES PATENT OFFICE.

SAMUEL W. BARR, OF MANSFIELD, OHIO.

SULKY-PLOW.

SPECIFICATION forming part of Letters Patent No. 295,613, dated March 25, 1884.

Application filed August 11, 1883. (No model.)

To all whom it may concern:

Be it known that I, SAMUEL W. BARR, of Mansfield, Richland county, Ohio, have invented a new and useful Improvement in Sulky-
5 Plows, which improvement is fully set forth in the following specification, reference being had to the accompanying drawings.

My invention relates to that form of sulky or riding plow in which the plow is constructed to conform to the attachments and the attachments combined with the plow in such a way as to form a complete machine. Neither can be separated without leaving the other valueless.

15 My invention consists, mainly, in a combination of levers for raising the point of the plow by means of a vertical hinge at the front end of the plow-beam, and in a horizontal hinge at the end of the beam to allow the team to 20 turn easily at corners and pull the plow around; also, in a combination draft-rod for gaging the depth of a plow.

Figure 1 is a side view of my sulky-plow, showing the combination draft-rod. Fig. 2 is 25 a top view, showing the relative position of the wheel *K*, beam, and mold-board. Fig. 3 represents a portion of the beam and a portion of the tongue connected by the hinges, and is a view from the opposite side of the 30 hinges of Fig. 1.

Similar letters refer to similar parts.

The beam *A* of my plow sets nearly over the center, and is firmly bolted at its rear end to a cast base that holds the share and 35 mold-board. The spindle of the wheel *K*, Fig. 2, is secured to a rear projection of this base, and the wheel runs on this spindle with its face side against the bank of the furrow, and forms one side of the sulky, a portion of the 40 landside, and carries the plow. The wheel is set with its front close to the mold-board, and has a small flange on the land-side edge of its rim to prevent slipping sidewise. Its diameter is such as to make the plow of usual length. 45 The bracket *P*, Fig. 2, is permanently secured to the beam, and has one end drilled and bent down at right angles to its side, and the lower end is thrown out till its face is parallel with the outside of the segment *Q*. The lever *g* is 50 formed with a disk at its fulcrum, and has a

short arm at nearly right angle, to the end of which the spindle for the wheel *Z* is riveted. A bolt holds it to the bracket *P*, and when the plow is doing its work the lever *g* stands nearly perpendicular and the wheel *Z* is opposite the wheel *K*. The lever *g* is provided with thumb-lever, spring-pawl, &c., for engaging the segment. The lever *F*, Fig. 1, is formed with a circular plate at its fulcrum, and a curved short arm, *J*, having a slot nearly 55 its whole length. The lever is provided with the usual devices for adjusting it. The notched plate *E* has two points on the opposite side, that rest on the beam to keep it from turning, and is held to the beam by the same bolt that 60 holds the lever *F*. The short arm of the lever, with its slot, is upon the cam principle, and when the lever is thrown forward the bolt of the bar *B* rides up the slot and lifts the bar. The bar *B* extends to the end of the beam, and 65 forms one half of the hinge *c*, the other half of which is bolted to the end of the tongue *D*. A bolt, *W*, through the end of the beam and 70 bar *B* forms the vertical hinge at the end of the plow-beam. The bar *B* and tongue, connected by the hinge *c*, constitute a rigid line 75 from the neck-yoke of the team to the lever *F*, and when the lever is thrown forward the end of the bar is raised, and the point of the plow also. In this operation the weight of the end 80 of the beam, double-trees, &c., falls on the wheel *K* and neck-yoke.

Fig. 3 represents a portion of the beam *A* and the rear end of the tongue, and is a view from the opposite side of Fig. 1. A top view 85 of this arrangement is shown at *m v n*, Fig. 2. The hinge-bar *m* is secured to the side of the tongue by the same bolts that hold the front portion of the hinge *c*, Fig. 1. The strap *n* has a notch in its upper edge to catch in the 90 staple *o*, and is knuckled with the bar *m* just in front of the hinge *c*. A spring, *t*, knuckled with the bar *m* at the same point, slides through the staple *o* below the strap *N*, and keeps the strap against the upper part of the staple. The 95 staple *o* is strong and fastened firmly to the beam *A*, and is of such size as to give said strap the requisite play. This check-hinge holds the tongue and beam rigidly in line, but when turning at corners the strap *N* is pressed 100

down by the driver's foot, disengaged, and the team can walk around and turn the plow while in the ground.

The side view of my sulky-plow, Fig. 1, shows 5 a new form of draft-rod for gaging the depth of a plow. The rod S is bolted to the beam A above the mold-board, and has a thread cut on its front end several inches back for a nut. A long clevis, H, with a hole in its end, 10 is placed on the rod, and a spiral spring, I, of suitable strength and size, is put on between the sides of the clevis, and the nut turned on the rod. The clevis extends forward on either 15 side of the curved beam projection R, and has a bolt in the front end for a hitch. A small roller is placed between the sides of the long clevis to move along the lower edge of the projection R. A pin in the lower end of the 20 projection prevents the clevis H from slipping off. The depth of furrow is gaged by the tension of this rod. If the spring is compressed enough to allow the plow to cut six inches 25 deep, and the plow is thrown up by any obstruction, the spring will expand and draw the roller up the curved projection R, and turn the point of the plow down. On the other hand, if the plow cuts seven inches deep, more power will be required to draw the plow, the spring will be compressed, and the roller

forced along the curve R, and the end of the 30 beam and point of the plow will be raised.

The operation of the rod on the curved projection will keep the plow at nearly a uniform depth. If the ground is hard, or a deeper furrow desired, the spring must be compressed 35 by turning the nut on the rod S, and vice versa for soft ground or shallow plowing.

Having fairly and fully described the several parts and functions of my sulky-plow, I 40 wish to secure by Letters Patent the following:

1. The combination, in a sulky-plow, with the pivoted bar B, of the tongue D, the hinge-plate e, the hinged bars M N, staple O, and spring T, substantially as shown and described. 45
2. The plow-beam A, pivoted to the bar B, and the curved projection R, in combination with the spring draft-rod H, roller h, and draft-clevis, substantially as set forth.
3. The combination, with the pivoted bar B, having pin b, of the lever F, having the curved slotted arm J, the rack E, plow-beam A, and wheel K, substantially as shown and described. 50

SAMUEL W. BARR.
